SPOON OR SIMILAR ARTICLE

James Russell Price, Esmond, R.I., assignor to Gorham
Division of Textron Inc., Providence, R.I.

Continuation-in-part of design application Ser. No.
19,088, Sept. 10, 1969. This application Aug. 4,
1970, Ser. No. 24,304

Term of patent 14 years

Int. Cl. D7—03

U.S. Cl. D54—12

FIG. 1

FIG. 2

FIG. 3

FIG. 4

FIG. 5

FIG. 6

FIG. 1 is a top plan view of the spoon or similar article showing my design;

FIG. 2 is a front elevational view thereof;
FIG. 3 is a right side elevational view thereof;
FIG. 4 is a rear elevational view thereof;
FIG. 5 is a left side elevational view thereof;
FIG. 6 is a bottom plan view thereof; and
FIG. 7 is an enlarged cross-section taken on line 7—7 of FIG. 2.

The design is intended for use on sets comprising forks, spoons, knives and similar articles of flatware.

This is a continuation-in-part of design application Ser. No. 19,088, filed Sept. 10, 1969, and now abandoned.

I claim:

The ornamental design for a spoon or similar article, as shown and described.
